UNITED STATES PATENT OFFICE.

FRANK BARUTIO, OF ST. LOUIS, MISSOURI.

BLADE-HOLDER.

1,206,499.

Specification of Letters Patent. Patented Nov. 28, 1916.

Application filed September 13, 1915. Serial No. 50,409.

To all whom it may concern:

Be it known that I, FRANK BARUTIO, a citizen of the United States, residing in the city of St. Louis, State of Missouri, have invented new and useful Improvements in Blade-Holders, of which the following is a specification, reference being had to the accompanying drawings.

My invention relates to devices for holding safety razor blades while the same are being honed, stropped or sharpened, and has for its main object the production of a simple and practical tool for this purpose, wherein blades of different patterns may be sharpened, and whereby the sharpening may be readily and quickly secured.

Another object is to provide a device for this purpose economical in manufacture, and convenient and practical in use.

With these and other objects in view, attention is called to the accompanying drawings, which are to be considered as part of these specifications, and wherein—

Figure 1 is a transverse section through another form of my improved device. Fig. 2 is a plan view of the form shown in Fig. 1 with a blade of the style known as a Gillette secured in place therein for sharpening. Fig. 3 is a plan view similar to Fig. 2 with a blade of a different style secured in place therein with the cutting edge extending from the side opposite the Gillette shown in Fig. 2. Fig. 4 is a face or side view of the form shown in Figs. 1, 2, and 3 in open position. Fig. 5 is an edge of the opened holder shown in Fig. 4. Fig. 6 is an edge view of the holder shown in Figs. 1 to 5 in closed position.

Referring more particularly to the drawings, A represents my improved holder as a whole, made up of the two flat members B and C, the two members B and C being hinged together at their extremities 1 and 2 by means of the hinge 3 in such manner that they, the members B and C, may be readily opened and spread apart, as shown, for the insertion or removal of the razor blade 4. The members B and C bear the longitudinal recesses as shown at 20 and 21, and the member C bears the circular recesses 6, the recess 20 being of exact size and shape to receive the thickened portion of one style of razor blade, and the recesses 21 and 6 being of size and shape to exactly conform to the openings or enlarged or thickened

portions of razor blades. The said studs 5 and the corresponding circular recesses 6 should be so located that the holes found in some makes of safety razor blades will exactly engage said studs 5 and allow the studs 5 to pass through the holes in the safety razor blade, and so as also to secure and hold the blade 4 centrally positioned between the two members B and C with the projecting edge 8 of said blade 4 approximately parallel to the front edge of the members B and C to readily permit and facilitate the act of sharpening. Likewise, the recesses 20 and 21 are so formed and shaped that said recesses will exactly receive and hold the shank of certain other styles of safety razor blades so that the edge of said blade will likewise be properly positioned in said holder for sharpening. An additional locking stud or pivotal latch 10 is located upon the member B toward the handle of the tool for the purpose of locking the member C in closed relation to the member B with the blade 4 held between them, or any other suitable locking mechanism may be substituted. The outer end of the member B may be equipped with any suitable handle, as 16, for convenience in use.

In actual use it will be seen that in sharpening the style of safety razor blade known as the Gillette style, all that is necessary is to spread the members B and C, set the blade 4 upon the studs 5, close down the member C, and lock the members C and B together by means of the locking stud 10, or where it is desired to sharpen the other common form of safety razor blade, that is to say a blade bearing a shank, all that is necessary is to place the shank of said blade within said recess 20, close down the member C upon the member B, and likewise lock the two members together by means of the locking stud 10. The tool A is then taken in the hand and the projecting edge 8 is applied to the strop or hone as desired in usual manner.

As shown in Fig. 1, the exterior faces or sides of the rectangular holding members B and C are tapered outwardly in opposite directions from a longitudinal line located and extending near the middle of the members, as shown in Fig. 1. The object of this is to make the tool double acting in that the cutting edge of a blade may project from either

side. This will be more clearly understood by referring to Figs. 2 and 3 in which a blade of the "Gillette" type is shown in the first mentioned Fig. 2 extending from one side of the holder while in Fig. 3 another style of blade such for instance as a "Gem" is shown with its cutting edge projecting from the opposite side of the tool. By referring to Figs. 2, 3, and 4 it will be noted that the holder is made slightly wider and longer than the blade which it is adapted to hold while being sharpened and that the two holding members are so formed that a razor blade of one style may be supported 15 on one side of a central longitudinal line drawn through the members with its edge projecting on one side of the members while a razor blade of another type can be supported on the opposite side of the central longitudinal line referred to with its edge 20 projecting on the opposite side of the members.

Although I have herein described and set forth certain specific manner and methods 25 of constructing and assembling the several elements of my invention, I reserve the right to modify same in minor details, not departing from the spirit of my invention, so as best to form my improved holder to meet 30 all practical demands.

As shown in Figs. 1, 2, 3, 4, 5 and 6 with the studs 5 and the corresponding circular recesses 6 located toward one edge of the holder A for the purpose of holding and 35 sharpening styles of safety razor blades bearing corresponding holes as shown in Fig. 2, and with the longitudinal recesses 20 and 21 located toward the opposite edge of the tool for the purpose of receiving and 40 holding the shank style of safety razor blade as shown in Fig. 3, the edges of said blade being turned toward and projecting from

one side or the other for the purpose of sharpening.

What I claim to be new and patentable is: 45

In a holder for safety razor blades, the combination of a rectangular holding member slightly wider and longer than the blade, and having short raised studs adapted to fit in the apertures of a certain style of safety blade; said studs being located on one side of a longitudinal line drawn centrally through the holding member and so arranged that a cutting edge of a blade held thereon will project beyond one side edge of the holding member and said holding member being also provided with a longitudinal recess located on the opposite side of a central line drawn through the holding member, to receive a thickened portion of another style of razor blade and to hold said blade with its cutting edge projecting beyond the opposite side edge of the holding member, a handle extending from one end of the holding member, a second holding member similar in size and form to the first mentioned member, said second holding member being adapted to be folded upon the first member to clamp a safety blade in interposed position, and being provided with circular recesses to receive the studs of the first member, and a longitudinal recess corresponding to and adapted to register with the longitudinal recess of the first member, a hinge connecting the outer ends of the two holding members, and a pivotal latch attached to the handle and adapted to be turned to lock the two members in clamping position. 70 75

FRANK BARUTIO.
